SEAL FOR ROTARY REGENERATOR

Raymond Smith, Fraser, Mich., assignor to Continental Aviation and Engineering Corporation, Detroit, Mich., a corporation of Virginia

Filed Oct. 25, 1961, Ser. No. 147,512

10 Claims. (Cl. 165—9)

This invention relates to heat exchangers and particularly to improved sealing means for a rotary regenerative type heat exchanger.

In a preferred rotary heat exchanger of the type used in turbine engines, an annular framework carrying a matrix of heat absorbent material rotates in a stationary casing. The matrix may be a drum-like annulus or a series of discs. In any event, the casing is divided radially into two sections which are, as far as possible, sealed from one another. The hot exhaust gases are directed into one of these sections and the cold compressed air is detoured through the other on its way to the combustion chamber. The matrix rotates in the paths of flow of both of these; the effect being that a large amount of heat from the exhaust gases is transferred to the compressed air. In this way, energy in the form of heat which would otherwise be lost is retained in the engine.

Efficiency is lost in such a heat exchanger unless an effective seal is provided between the casing and the rotating matrix to minimize the intermixing of the air and the exhaust gases. Since the air has been compressed a pressure drop resulting from leakage of the air into the lower pressure exhaust represents a direct loss of the energy produced in compressing.

Such a seal must be constructed in a manner which will compensate for the distortion and warping which occurs due to the fact that the different parts of the apparatus are subjected to varying as well as intense heats during operation. Further, the seal should be constructed so that the effect of friction is minimized.

In an exchanger employing a drum matrix as discussed herein, the paths of flow of the hot gases is generally radially outwardly through the matrix. The cold air, on the other hand, flows radially inwardly through the matrix. The inner ring of the matrix then receives the hot gases as well as the heated air while the outside ring receives the cold air as well as the gases after the heat has been substantially removed. These paths of flow then produce a "hot" ring and a "cold" ring, producing a distortion or warping in the form of an expanded inner ring. Any seal utilized must take into consideration this fact and therefore must include some thermal compensating means to overcome it.

Heretofore, attempts at providing a seal for this type of heat exchanger have not been too successful. Generally, these seals have consisted of a flexible seal projecting from the casing in contact with and acting to wipe the rotating matrix. During operation, the distortion and warping described above tends to separate the matrix and casing more and more as the apparatus gets hotter and hotter. Thus such a seal, to be effective in the hot stages of operation, must bear too hard against the matrix in the colder stages. Energy saved by an effective seal while the apparatus is hot is lost through increased friction while the regenerator is cold.

An object of the present invention is to provide a novel seal which effectively separates the exhaust gases and air at all stages of operation through the provision of a thermal compensating structure.

Another object of the present invention is to provide an improved sealing means for a rotary regenerative heat exchanger utilizing vanned rollers to effectively seal

2

the air and gases from each other at all times during operation.

Still another object is to provide an effective sealing means which minimizes friction at all times during operation by utilizing a rolling seal.

Other objects of the invention will readily occur to those skilled in the art upon reference to the accompanying drawings showing a preferred embodiment of the present invention in which like characters refer to like parts throughout the several views and in which

FIG. 1 is a perspective diagrammatic view of a structure embodying the present invention from which parts of the assembly immaterial to the understanding of the invention have been omitted.

15 FIG. 2 is a cross-sectional view of a rotary regenerator embodying the present invention taken substantially on the line 2—2 of FIG. 3.

FIG. 3 is a cross-sectional view taken substantially on line 3—3 of FIG. 2.

20 FIG. 4 is a longitudinal cross sectional view of a roller embodying the invention and,

FIG. 5 is a cross sectional view taken substantially on line 5—5 of FIG. 4.

25 Referring first to FIG. 1 for a general description of the regenerator, it comprises an annular matrix 10 in the form of a drum, the edges of the drum being defined by end rings 11 capped by annular retainers 12A and 12B. Gear teeth 13 are provided on the outer peripheral edge of one of the annular retainers 12A. The heat exchange portion 14 of the matrix 10 is fixed between the end rings 11 and may be of any suitable heat absorbent material known in the art such as thin corrugated sheets of metal. A bulkhead assembly 15 divides the regenerator into two sections. The regenerator housing and other structures by which the air and gas flow is directed have been omitted from FIG. 1 in order to more clearly illustrate the general arrangement of a regenerator embodying the present invention.

30 Referring now to FIGS. 2 and 3 for a more detailed description of the apparatus embodying the present invention, a casing 16 cooperates with the bulkhead assembly 15 and duct work (not shown) to form passageways which direct the flow of gas and air through the regenerator. As indicated by the arrows at A in FIG. 40 45 50 55 60 65 70

2, air discharged from a compressor (not shown) flows radially inwardly through the heat exchange material 14 and leaves the regenerator axially. Exhaust gases, as indicated by the arrows at B, are discharged from a turbine (not shown) and enter the regenerator axially, flowing radially outwardly through the material 14.

The casing 16 rotatably carries a drive shaft 17 by any means such as a pair of bearings 18. An extended portion 17A of the drive shaft 17 may be connected to any convenient driving means such as a turbine (not shown).

55 The drive shaft 17 extends through a spacer tube 19 which fixes in spaced relation a pair of friction rings 20. A jam nut 21 cooperates with an annular boss 22 in the drive shaft 17 to secure the friction rings 20 and the spacer tube 19 to the shaft 17. The rings 20 and tube 19 may be prevented from rotating relative to the shaft 17 by any convenient means such as a key 23.

60 65 70 75 80 85 90 95

The bulkhead assembly 15 comprises a substantially convex partition plate 24 carrying a cylindrical housing 25 at a pair of opposite edges by any convenient means such as bolts 26. The housings 25 are adapted to enclose a roller assembly 27 to be described more fully below. A longitudinal sector is removed from each cylindrical housing 25 forming a slotted portion 28 exposing the roller assembly 27 to the inner lateral wall of the matrix 10. The partition plate 24 is secured to the casing 16 by any convenient means such as bolts 29.

Cylindrical housings 25A, similar to the housings 25 but preferably somewhat larger, are secured to the casing 16 by any convenient means such as bolts 30. These too are constructed to enclose a roller assembly 27A like roller assembly 27 but again somewhat larger. A slot 28A provided in the housing 25A exposes each roller assembly 27A to the outer peripheral wall of the matrix 10 in substantial alignment with the slot 28 provided in the housing 25.

A circumferential seal assembly 33 of any preferred type well known in the art may be provided to wipe against the annular retainers 12 as best illustrated in FIG. 2.

Now referring to FIG. 4 for a more detailed description of the roller seal of the present invention, the reference character 27 indicates generally the roller assembly previously referred to. FIG. 1 clearly shows the position of this assembly with respect to the other parts of the regenerator. The assembly 27 comprises a shaft 34 rotatably secured to the casing 16 by any convenient means such as bearing assemblies 35 carried by cap screws 36. A geared ring 37 is positioned on the shafts 34 to mesh with the gear teeth 13 provided on the matrix 10 by means of a spacer tube 38. Annular spacer elements 39 are disposed on the shaft 34 between the spacer tube 39 and a second spacer tube 38A. A cap element 40 acting with the spacer tube 38 and the spacer tube 38A positions the annular spacer elements substantially in alignment with the lateral edge of the matrix 10. This assembly may be fixed to the drive shaft 34 by any means which prevents relative rotation such as a key 41.

Each of the spacer elements 39 is provided with a plurality of annularly spaced radially extending aligning slots 42 as best seen in FIG. 5. Each of these is designed to take a vane assembly 43. A wave spring 44 acting with a seat spring 45 urges the vane assembly 43 outwardly.

The vane assembly 43 comprises a plurality of substantially rectangular vane seals 46 each provided with slots 47 in each lateral edge. These slots 47 align with annular grooves 48 provided in each end of the spacer elements 39. Rings 49 retained in the grooves 48 of adjacent spacer elements 39 pass through the slots 47 and act to retain the individual vane seals 46 in the slots 42.

Each of the roller assemblies 27 and 27A are constructed substantially in the manner described above except that the assembly 27A is preferably larger as heretofore indicated.

In operation the friction rings 20 frictionally contact the end rings 11 to rotatably drive the matrix 10, although it is apparent that any one or more of the roller assemblies 27 and 27A could be drivingly connected to a source of power and used to rotate the matrix 10 without the need for the friction rings 20. This rotational force is transmitted to the roller assemblies 27 and 27A by the geared retainer 12A and the geared rings 37. The springs 44 and 45 urge the vane assemblies 43 into rolling contact with the matrix 10 as each individual vane assembly 43 is rotated into communication with the slots 28 provided in the housings 25. The vane slots 42 are spaced such that at least one vane assembly 43 is in contact with the matrix at all times, thus providing an effective sealing action.

The segmented nature of the vane assemblies 43 enables them to adapt themselves to the distortion and warping which will take place in the matrix as the regenerator becomes heated. The wave spring 44 is designed to apply tension to each individual vane element 46 enabling it to extend or retract where warping or distortion occurs. The rings 49 bind the vane seals 46 together sufficiently to maintain a line contact with the matrix 10 at all times. The rolling contact of the seals minimizes the effect of friction especially in the colder stages of operation where

heretofore friction had to be great to compensate for the warping present in the hotter stages.

It will be apparent to those skilled in the art from the foregoing description that the thermal compensating seal of the present invention is highly advantageous in reducing leakage and friction in rotary regenerators and thereby increasing the efficiency of machines in which it is employed. The simplicity of structure which the present invention enables is also an important advantage.

It will also be apparent to those skilled in the art that while only one preferred form of the invention has been illustrated and described, various changes and modifications in construction may be had without departing from the spirit of the invention or from the scope of the appended claims.

I claim:

1. In a regenerative heat exchange apparatus
  - (a) a casing,
  - (b) a matrix of heat absorbent material rotatably carried in said casing,
  - (c) means for partitioning said casing into at least two sections,
  - (d) rollers rotatably carried in said casing intermediate said sections,
  - (e) sealing means disposed in said rollers in sealing contact with said matrix,
  - (f) each of said rollers comprising,
    - a shaft rotatably secured to said casing,
    - a spacer tube carried at each end of said shaft,
    - a plurality of axially aligned annular spacer elements disposed between said spacer tubes and fixed to said shaft for rotation therewith,
    - the ends of said spacer elements being provided with axially aligned annular grooves,
    - retaining rings carried in said annular grooves of adjacent spacer elements, and
    - said spacer elements being provided with a plurality of aligned annularly spaced radially extending slots, and
  - (g) said sealing means being carried in said slots and each of said sealing means comprising
    - a plurality of substantially rectangular vane elements carried in each of said slots,
    - grooves being provided in the lateral edges of said vane elements in registry with said grooves provided in said spacer elements,
    - said retainer rings being received by said vane element grooves whereby said vane elements are retained in said slots, and
    - means urging each of said vane elements outwardly whereby said individual vane elements will be urged into contact with said matrix and said retaining rings will bind adjacent vane elements together sufficiently to maintain a line contact with said matrix.
2. In a regenerative heat exchange apparatus
  - (a) a casing,
  - (b) a matrix of heat absorbent material rotatably carried in said casing,
  - (c) means for partitioning said casing into at least two sections,
  - (d) rollers rotatably carried in said casing intermediate said sections,
  - (e) sealing means disposed in said rollers in sealing contact with said matrix,
  - (f) each of said rollers being provided with a plurality of annularly spaced radially extending slots and a plurality of axially spaced axially aligned retainer rings passing through said slots,
  - (g) said sealing means being carried in said slots and each of said sealing means comprising
    - a plurality of vane elements carried in each of said slots and each of said vane elements having edges extending radially with respect to said roller,

- grooves being provided in said edges and receiving said retainer rings whereby said vane elements are retained in said slots, and means carried in said slots and urging said vane elements radially outwardly.
3. In a regenerative heat exchange apparatus
- a casing,
  - an annular matrix rotatably carried in said casing and having inner and outer peripheral walls,
  - means for rotating said matrix,
  - a partition plate secured to said casing dividing said casing into two sections,
  - substantially cylindrical housings carried at opposite edges of said partition plate and each of said cylindrical housings being provided with an elongated 15 radially extending slot disposed closely adjacent said inner peripheral wall of said matrix,
  - a roller member rotatably secured to said casing and carried in each of said housings,
  - each of said roller members being provided with a 20 plurality of radially extending annularly spaced slots,
  - a vane assembly carried in each of said roller member slots,
  - each of said vane assemblies comprising a plurality 25 of vane elements, retaining means carried by said roller member and resiliently securing adjacent vane elements one to the other and means resiliently urging said vane elements radially outwardly.

4. The heat exchanger apparatus as defined in claim 3 and in which said retaining means comprises a plurality of retainer rings, said vane elements being substantially rectangular, slots being provided in the lateral edges of said vane elements, and said retaining rings passing through the slots of adjacent vane elements whereby to allow each of said vane elements to be independently urged by said urging means while at the same time maintaining substantial line contact between said vane elements and said matrix.

5. The heat exchanger apparatus as defined in claim 3 and in which said urging means comprises a wave spring 40 and a seat spring, said springs being disposed in said roller whereby said wave spring acts to urge each of said vane elements outwardly.

6. The heat exchanger apparatus as defined in claim 3 and in which said rotating means comprises a drive shaft 45 adapted for connection with a source of power, said drive shaft being rotatably carried in said casing, friction rings carried in spaced relation on said drive shaft, means for

preventing relative rotational movement between said drive shaft and said friction rings, said matrix comprising a pair of annular retainers, said friction rings being disposed in frictional contact with said annular retainers whereby rotational force applied to said drive shaft is transmitted to said matrix.

7. In a heat exchanger apparatus having a casing providing at least two sections and a matrix rotating in said sections, a sealing means engaging said matrix to seal one section from the other and comprising

- a roller adapted to be rotatably carried in said casing closely adjacent said matrix,
- said roller being provided with a plurality of annularly spaced radially extending slots,
- a plurality of vane elements carried in each of said slots,
- retaining means carried by said roller and resiliently securing adjacent vane elements one to the other, and
- means resiliently urging said vane elements radially outwardly into contact with said matrix.

8. The sealing means as defined in claim 7 and in which said retaining means comprises

- a plurality of axially spaced rings carried by said roller,
- slots being provided on the adjacent edges of each pair of said vane elements, and
- each of said slots of adjacent vane elements receiving one of said rings.

9. The sealing means as defined in claim 7 and in which 30 said roller comprises

- a plurality of axially aligned annular spacer elements,
- slots being provided in said spacer elements.

10. The sealing means as defined in claim 9 and in 35 which said retaining means comprises

- a plurality of axially spaced rings carried by said annular spacer elements,
- slots being provided on the adjacent edges of each pair of adjacent vane elements,
- each of said slots of adjacent vane elements receiving one of said rings.
